CLAIM

The ornamental design for a deltoid cup for football shoulder pad, as shown and described.

DESCRIPTION

FIG. 1 is a front perspective view of a deltoid cup for football shoulder pad showing my new design;

FIG. 2 is a front elevational view thereof;

FIG. 3 is a side elevational view thereof, the opposite

side being a mirror image;

FIG. 4 is a bottom plan view thereof; and

FIG. 5 is a top plan view thereof.

The undisclosed rear is plain and unornamented.

FIG. 1.FIG. 3.FIG. 2.FIG. 4.FIG. 5.
